UNITED STATES PATENT OFFICE.

FRED HELL WARD, OF WASHINGTON, DISTRICT OF COLUMBIA.

COMBINATION LOCK AND CONTROLLER FOR SIDE DOORS OF BOX-CARS.

1,379,495.

Specification of Letters Patent. Patented May 24, 1921.

Application filed June 29, 1920. Serial No. 392,767.

To all whom it may concern:

Be it known that I, FRED H. WARD, a citizen of the United States, and a resident of Washington, in the District of Columbia, 5 have invented certain new and useful Improvements in a Combination Lock and Controller for Side Doors of Box-Cars, of which the following is a specification.

My invention relates to an improvement 10 in car doors.

The object of the invention is to provide an improvement of this character in which the doors of the car are constrained to corresponding movement whereby when one of 15 the doors is secured in desired position the other of said doors is automatically secured in corresponding position and in which manipulation of the doors by an unauthorized person is effectively precluded.

Another object is to provide a device of 20 this character of simple and durable construction reliable in operation and easy and inexpensive to manufacture.

Other objects and advantages of the invention reside in certain novel features of 25 construction, combination and arrangement of parts which will be hereinafter more fully described and particularly pointed out in the appended claims, reference being had 30 to the accompanying drawings forming part of this specification and in which:

Figure 1 is a plan view of my improvement, the car being shown in section and broken away for the sake of illustration; 35 and

Fig. 2 is a detail perspective view of the improvement and one of the car doors.

Referring to the drawings it will be seen 40 that my invention contemplates a car, indicated generally at 10, and including side walls 11 and 12 having door openings 13 and 14, respectively, therein. A door 15 is provided for the opening 13 and a door 16 is provided for the opening 14. Both 45 the doors 15 and 16 are mounted for sliding movement but in opposite directions, the door 15 being mounted to slide to closed position shown in Fig. 1 in the direction of the arrow and the door 16 being mounted 50 to slide to closed position shown in Fig. 1 in the opposite direction which is also indicated by an arrow. The doors are suspended from the structure of the car in any well known or conventional manner.

55 Controlling means for the doors is provided, and consists of a tubular rod 17 closed

at one end, as indicated at 18, and opened at the opposite end, as indicated at 19. The tubular rod 17 is arranged to extend transversely of the car, as shown in the drawings. The tubular rod is supported for sliding movement in a sleeve 20 depending from a swivel bracket 21 which is in turn carried by the cross bar 22 secured to beams B or other suitable portions of the car structure. The beams B are secured to or form part of the car structure and are arranged to extend longitudinally of the car above the door openings. The cross bar 22 extends between and is suitably secured to the beams. The sleeve 20 of the swivel bracket thus depends below the cross bar and the rods 17 and associated instrumentalities to be hereinafter fully described are thus arranged below the cross bar and below the beams. The sleeve 20 embraces the periphery of the tubular rod 17 so as to slidably receive the same.

The closed end 18 of the tubular rod is provided with a preferably integral, vertically-disposed, eye 23. A horizontally disposed eye 24 is carried by a shank 25 which extends through the door structure as shown in Fig. 1. Suitable plates 26 coöperate with the door structure to secure the shank in position. The eyes 23 and 24 are interengaged whereby the tubular rod 17 is free to partake of relative swinging motion in a horizontal plane with respect to the door 15. This connecting means constituted by the eyes 23 and 24 and the associated structure also provides for a small degree of lost motion in a vertical direction to occur between the tubular rod and the door 15.

A rod 27 is telescopically received in the opening of the tubular rod 17, being free to partake of sliding motion in the opening of the tubular rod. The outer end of the rod 27 is provided with a vertically disposed eye 28, preferably formed integral with the rod 27. This eye 28 is interengaged with a horizontally disposed eye 29 carried on the end of a shank 30 which extends through the structure of the door 16 and is secured in position by means of the spaced plate 31 or other suitable fastening means. The connection or connecting means afforded by the interengaged eyes 28 and 29 permits the rod 27 to swing in a horizontal plane relative to the door 16 and also provides for a small degree of lost motion in a general vertical direction.

Locking means 32 of conventional construction is provided for either of the doors 15 or 16 but is shown for the sake of illustration as coöperating between the door 16 and the associated car structure. Only a single locking means is necessary as the locking action of this locking means is effective or active through the controlling means to the other door.

10 In practice, to move the doors from the closed position shown in Fig. 1 to the open position shown in the same figure, it is necessary that both the doors 15 and 16 be grasped and pushed or otherwise forced 15 in opposite directions. When the doors are so acted upon they slide toward the dotted line position, the rod 27 sliding or telescoping to a greater extent within the tubular rod 17 and both the rod 27 and the tubular 20 rod 17 swinging relative to the doors 16 and 15, respectively, and carrying with it the swivel bracket 21 until the doors are pulled open and all of the parts occupy the position shown in dotted lines in Fig. 1.

25 It is to be noted that it is essential and is required that two operators act together to open the doors and this in a large measure precludes theft or any manipulation of the doors by an unauthorized person as 30 when one person endeavors to open the doors the push which he exerts upon one of the doors due to the drag of the other door serves only to tilt or cant the door upon which he is acting and so increases the 35 resistance that it is practically an impossibility to effect an opening movement of the doors.

Another important feature resides in the fact that it is only necessary to provide a 40 single locking means in order to effect a complete locking action of both doors and the locking action of a single means is effectively transmitted by the controlling means to the other door. Moreover, this is 45 true in any position in which it is desired to secure the door.

I claim:

1. In combination with a car having a door opening in each of its opposite side 50 walls, oppositely sliding doors for said openings and locking means for one of said doors, controlling means for said doors comprising a tubular rod closed at one end, means for slidably supporting the tubular 55 rod from the roof of the car including a sleeve embracing the rod and pivotal connection from the sleeve to the roof, means for connecting the closed end of the tubular rod to one of said doors consisting of a 60 horizontally disposed eye secured to the door and a vertically disposed eye carried by the closed end of said tubular rod and interengaged with the eye secured to the door, a rod telescopically received in the 65 opening of the tubular rod, and means for

securing the rod to the other of said doors including a horizontally disposed eye secured to said last-mentioned door and a vertically disposed eye carried by the rod and interengaged with the eye of said last mentioned door. 70

2. In combination with a car having a door opening in each of its opposite side walls, oppositely sliding doors for said openings and locking means for one of said doors, controlling means for said doors including a tubular rod, means for slidably securing the tubular rod from the roof of the car, means for connecting one end of the tubular rod to one of said doors, whereby 75 the tubular rod may partake of swinging motion with respect to said door in a horizontal plane, a rod slidably and telescopically received in said tubular rod, and means for connecting the free end of said 80 rod to the other of said doors whereby it is free to partake of relative horizontally swinging motion with respect to said last mentioned door.

3. In combination with a car having a 90 door opening in each of its opposite side walls and oppositely sliding doors for said door openings, controlling means for said doors including telescopic rods, means for supporting the outer of said telescopic rods 95 from the roof of the car, and separate means for connecting the free end of each of said telescopic rods to the respective doors.

4. In a device of the character described including oppositely sliding doors, controlling means for said doors comprising a tubular rod, means for slidably supporting said tubular rod, means for connecting one end of said tubular rod to one of said doors, a rod slidably and telescopically received 100 in said tubular rod, and means for connecting the free end of said rod with the other of said doors.

5. In a device of the character described including oppositely sliding doors, controlling means for said doors, including telescopic rods, means for supporting said telescopic rods, and means for connecting the free end of each of said telescopic rods to 110 its respective door.

6. In a device of the character described including oppositely sliding doors, controlling means for said doors including telescopic rods, and means for connecting the free end of each of said telescopic rods to 115 its respective door.

7. In a device of the character described including oppositely sliding doors and locking means for one of said doors, controlling means for said doors including telescopic rods, means for supporting said telescopic rods, and means for connecting the free end of each of said telescopic rods to its 120 respective door.

FRED HELL WARD.
